UNITED STATES PATENT OFFICE.

JOHN F. HEMENWAY, OF NEW YORK, N. Y.

PRESSURE-RELEASE FOR CLOTHES-WRINGERS.

1,220,112.

Specification of Letters Patent. Patented Mar. 20, 1917.

Application filed July 26, 1916. Serial No. 111,403.

To all whom it may concern:

Be it known that I, JOHN F. HEMENWAY, a citizen of the United States, residing at New York city, in the county of New York and State of New York, have invented certain new and useful Improvements in Pressure-Release for Clothes-Wringers, of which the following is a specification, reference being had therein to the accompanying drawing.

10 This invention relates to certain new and useful improvements in pressure release for clothes wringers, the object being to provide a releasing device in which the movably mounted top bar of the wringer frame operates the releasing means in order that the pressure on the rolls can be instantaneously released.

Another object of my invention is to provide a pressure release which is exceedingly simple and cheap in construction, and one which can be readily incorporated in the ordinary construction of clothes wringer now in use.

25 Another object of my invention is to provide a movably mounted bar for the pressure screws held in position within the wringer frame by an expandible resilient member carried by the top bar in such a manner that when the top bar is forced downwardly the resilient member is expanded in order to release the bar carrying the pressure screws.

Other and further objects and advantages 35 of the invention will be hereinafter set forth and the novel features thereof defined by the appended claims.

In the drawings,

Figure 1 is a side elevation of a clothes 40 wringer frame in section showing the application of my improved pressure release thereto.

Fig. 2 is a perspective view of one of the members carried by the wringer frame detached, and

Fig. 3 is a perspective view of an end portion of the releasing spring and the guide member therefor.

Like numerals of reference refer to like 50 parts in the several figures of the drawing.

In carrying out my invention, I employ a wringer frame 1 formed of slotted side bars 2 connected together at their lower ends by a rod 3 and connecting members 4. The upper 55 ends of the slotted side bars carry a movably

mounted top bar 5 which is slidably mounted within the slotted upper end portions of the side bars 2 in order to allow the same to move vertically within the side bars for the purpose hereinafter fully described.

Secured over the upper end portions of the side bars 2 of the wringer frame are channel members 6 which embrace the side bars 2 and extend upwardly beyond the upper end thereof, and are provided with horizontally disposed flanges 6' for limiting the upward movement of the top bar 5.

Mounted within the lower portions of the slotted side bars 2 are bearings 7' in which the shaft 7 of the lower pressure roll 8 is mounted, said shaft being adapted to be driven by a crank or a drive pulley. Arranged above the lower pressure roll 8 is an upper pressure roll 9 carried by a shaft 10 mounted in bearings 11 arranged in the slots 75 of the side bars 2, the shafts 7 and 10 being preferably provided with meshing gears, not shown, preferably inclosed by gear casings 12.

Secured in the bearings 11 are spring supports 13 on which are mounted the lower ends of the pressure springs 14 on the upper ends of which are arranged bearing plates 15 carried by a pressure bar 16, said plates being provided with depending stud portions 17 extending into the coil springs 14 for holding the pressure springs in their proper position within the slots of the side bar 2 of the wringer frame.

Slidably mounted in the slotted side bars 2 of the wringer frame above the pressure bar 16 is a bar 18 which is provided with threaded boxes 19 in which are mounted the threaded portions of the pressure screws 20, the lower ends of which engage the plates 15. The upper portions of said pressure screws extend through openings 21 formed in the top bar 5 of the wringer frame so as to allow the top bar to move independently of the pressure screws for the purpose hereinafter 95 fully described.

In order to provide means for holding the intermediate bar 18 carrying the pressure screws 20 in a predetermined position so as to allow the pressure screws to exert the proper pressure on the pressure springs, I provide the top bar 5 with a bowed spring 22 which is secured centrally to the underside thereof and projects through guide members 23 carried by the underside of the 105 110

top bar 5 which are in the form of angle brackets having their vertically disposed portions slotted to receive the spring 22, said springs being provided with slots 24 through 5 which the pressure screws 20 pass in order to allow the spring to have free movement independent of the screws. The channel members 6 are provided with slots 25 from the bottom walls of which project headed studs 10 26 adapted to coöperate with the key-hole slots 27 formed in the ends of the spring 22 so that when the wringer is in the position shown in Fig. 1, the narrow portions of the key-hole slots 27 will be under the headed 15 studs 26, of the channel members 6 so as to prevent upward movement of the intermediate bar 18.

When it is desired to instantaneously release the pressure on the pressure rolls in 20 case of accident by striking the top bar 5, the spring 22 will be elongated so as to bring the enlarged portions of the key-hole shaped slots 27 in vertical alinement with the headed studs 26 which will allow the bar 18 to 25 move vertically within the wringer frame so as to release the pressure on the pressure rolls, the upward movement of the top bar being limited by the horizontally disposed flanges 6' of the channel members 6 so as to 30 prevent the part from becoming detached from the wringer frame. After the pressure has been released, and it is desired to reset the wringer in order to hold the intermediate bars in a predetermined position 35 by loosening the pressure screws and forcing downwardly on the top bar, the spring can be placed in position over the headed studs so that the pressure screws can be tightened to exert the desired pressure on the 40 pressure rolls.

From the foregoing description it will be seen that I have provided a pressure release for clothes wringers in which the pressure screws are carried by the intermediate bar 45 held in a predetermined position by a wringer frame and by a resilient expandible member carried by a movable top bar so that in order to release the pressure on the pressure rolls, it is only necessary to force the 50 top bar downwardly.

I claim:

1. A clothes wringer, comprising a frame having pressure rolls and pressure means for said rolls, a resilient member having 55 means for normally holding said pressure means in predetermined position, and a movably mounted top bar connected to said resilient member for releasing said pressure means.
2. A clothes wringer, comprising a frame having pressure rolls and pressure means for said rolls, an intermediate bar mounted in said frame having means for adjusting said pressure means, a resilient member having 65 means for normally holding said interme-

diate bar in predetermined position, and a top bar connected to said resilient member for releasing said pressure means.

3. A clothes wringer, comprising a frame having pressure rolls and pressure means 70 for said rolls, an intermediate bar having means for adjusting said pressure means, headed studs carried by the side bars of said frame, a movably mounted top bar, and a bowed spring carried by said top bar having openings coöperating with said headed studs for holding said intermediate bar in predetermined position within said frame.

4. A clothes wringer, comprising a frame having pressure rolls and pressure means 80 mounted therein, an intermediate bar mounted in said frame having pressure screws for adjusting said pressure means, headed studs carried by the side bars of said frame, a movably mounted top bar mounted in said frame, and a bowed spring carried by the top bar having slots in the ends thereof provided with reduced end portions coöperating 85 with the headed stud for holding and releasing said intermediate bar.

5. A clothes wringer, comprising a frame having pressure rolls and pressure means mounted therein, an intermediate bar mounted in said frame having pressure screws for adjusting said pressure means, slotted members carried by the side bars of said frame 95 provided with headed studs, a movably mounted top bar mounted in said frame, and a bowed spring carried by the top bar having slots in the end thereof provided with reduced end portions coöperating with the headed studs for holding and releasing said top bar.

6. A clothes wringer, comprising a frame having pressure rolls and pressure means 105 for said rolls, an intermediate bar having means for adjusting said pressure means, members carried by the side bars of said frame, a movably mounted top bar, and a resilient expandible member carried by the top 110 bar having means coöperating with the members carried by the side bars of said frame for holding said pressure means in predetermined position.

7. A clothes wringer, comprising a frame 115 having pressure rolls and pressure means mounted therein, an intermediate bar mounted in said frame having pressure screws for adjusting said pressure means, channel members secured to the side bars of said frame 120 and extending upwardly beyond the ends thereof, provided with slots having headed studs, a movably mounted top bar mounted within said frame, and a resilient expandible member carried by said top bar having key- 125 hole shaped slots coöperating with said headed studs for holding and releasing said intermediate bar.

8. A clothes wringer, comprising a frame having pressure rolls and pressure means 130

for said rolls, a resilient expandible member having means for normally holding said pressure means in predetermined position, and a movably mounted top bar arranged in 5 said frame co-acting with said expandible member for releasing said pressure means.

9. A clothes wringer, comprising a frame having pressure rolls and pressure means mounted therein, a bar mounted in said 10 frame having pressure screws for adjusting said pressure means, members secured to the side bars of said frame having vertically disposed headed studs, a movably mounted top bar mounted within said frame, and a bowed spring carried by said top bar having 15 slots with reduced portions co-operating with said headed studs for holding and releasing said bar.

10. A clothes wringer, comprising a frame 20 having pressure rolls and pressure means for said rolls, a resilient expandible member having means for normally holding said pressure means in predetermined position, a movably mounted top bar carried by said 25 resilient expandible member, and means for limiting the upward movement of said top bar.

11. A clothes wringer, comprising a frame 30 having pressure rolls and pressure means mounted therein, an intermediate bar mounted in said frame, having pressure screws for adjusting said pressure means, a resilient expandible member for holding said intermediate bar in predetermined position, 35 and a top bar carried by said resilient expandible member.

12. A clothes wringer, comprising a frame 40 having pressure rolls and pressure means mounted therein, a top bar slidably mounted within said frame, channel members secured to the side bars of said frame having hori-

zontally disposed flanges for limiting the upward movement of said top bar, an intermediate bar carrying pressure screws for adjusting said pressure means, and a resilient 45 expandible member carried by said top bar having means for normally holding said intermediate bar in predetermined position within said wringer frame.

13. A clothes wringer, comprising a frame 50 having pressure rolls and pressure means mounted therein, an intermediate bar slidably mounted in said frame having pressure screws for adjusting said means, channel members secured to the side bars of said 55 frame having slots provided with vertically disposed headed studs, a movably mounted top bar mounted in said frame, and a bowed spring having substantially key-hole shaped slots in the ends thereof embracing said 60 headed studs for holding and releasing said intermediate bar within said frame.

14. A clothes wringer, comprising a frame having pressure rolls and pressure means mounted therein, a top bar for said frame 65 having a resilient expandible member carried thereby, an intermediate bar carrying pressure screws for adjusting said pressure means, said resilient expandible member being provided with substantially key-hole 70 shaped slots, and channel members carried by the side bars of said frame having headed studs co-operating with said key-hole shaped slots for holding said intermediate bar in predetermined position within said wringer 75 frame.

In testimony whereof I hereunto affix my signature in the presence of two witnesses.

JOHN F. HEMENWAY.
